(57) **CLAIM**

The ornamental design for an LED light with tripod stand, as shown and described.

DESCRIPTION

FIG. 1 is a perspective view of an LED light with tripod stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 shown in FIG. 1;

FIG. 10 is a partial enlarged view of portion 10 shown in FIG. 1;

FIG. 11 is a partial enlarged view of portion 11 shown in FIG. 2;

FIG. 12 is a partial enlarged view of portion 12 shown in FIG. 2; and,

FIG. 13 is a partial enlarged view of portion 13 shown in FIG. 2.

The broken lines in the drawings depict portions of the LED light with tripod stand that form no part of the claimed design.
